UNITED STATES PATENT OFFICE.

ROBERT FARIES, OF DECATUR, ILLINOIS.

MACHINE FOR FORMING INTERLOCKING EYES.

SPECIFICATION forming part of Letters Patent No. 397,175, dated February 5, 1889.

Application filed September 29, 1888. Serial No. 286,735. (No model.)

To all whom it may concern:

Be it known that I, ROBERT FARIES, of the city of Decatur, county of Macon, and State of Illinois, have invented certain new and useful Improvements in Machines for Forming Interlocking Eyes, of which the following is a specification.

As heretofore constructed machines for forming interlocking eyes have employed a rotating head to coil the ends of the wires around a stud and form the interlock. This construction has necessitated the introduction of a device to raise the ends over the bodies of the wires; or, in the absence of such device, the ends have been raised by the hands of the operator attending the machine. The inconvenience and loss of time attending the raising the ends by hand are manifest, and the introduction of an auxiliary device that would automatically perform that operation has been difficult and somewhat unsatisfactory. In my invention the rotating head is dispensed with, and the interlock is formed by two pairs of levers that act in vertical planes while describing arcs having approximately-horizontal chords. The wires to be interlocked lie in about the same horizontal plane on opposite sides of the stud, with their ends projecting beyond the stud in opposite directions, and they are held more or less firmly against longitudinal and lateral misplacement. The pair of levers first to act are pivoted below the wires and swing in planes at right angles thereto. In their initial motion they strike the ends of the wires while moving slightly upward, carrying them over the bodies and bending them about one-fourth around the stud. The pair of levers second to act are pivoted above the wires and swing at right angles to the paths of the first pair of levers. In their action they carry the ends of the wires about one-fourth farther around the stud and slightly depress them. The interlock is completed by a second action of the first pair of levers on interchanged ends.

The operation of the levers is performed by a succession of quick strokes that bend the ends around the stud without tending materially to draw the wires lengthwise, and this is an advantage over the rotating heads which by continuous friction tend to draw the

wires lengthwise and prevent nice accuracy in spacing the distance between eyes.

From the above it will appear that the 55 principal objects of my invention are to produce a machine that will carry the ends of the wires over the bodies thereof while forming the interlocking coils, and that will not tend to draw the wires lengthwise during 60 such operation. Other features of less importance will appear in the detailed description and in the claims.

In the drawings accompanying and forming a part of this specification, Figure 1 is a 65 front elevation of a machine embodying my invention. Fig. 2 is a front elevation of the novel features of the machine enlarged and detached. Fig. 3 is a section on broken line z z in Fig. 2. Fig. 4 is a side elevation of my 70 device with the first move made in the formation of the interlock. Fig. 5 is the same view showing the second move made. Fig. 6 is the same view showing the third move made. Fig. 7 is a face view of certain parts, 75 showing their position at the stage of the operation shown in Fig. 6. Fig. 8 is a plan of the wires, the stud, the standard, and the handle used to operate the stud and standard, the wires being arranged preparatory to forming the interlock. Fig. 9 is the same plan showing the wires cramped by projections on the standard. Fig. 10 shows the position of the wires when the machine is first put in the condition shown in Fig. 5, the broken lines 80 and arrows indicating, as in subsequent figures, the directions the operative ends of the levers have pursued. Fig. 11 shows the position of the wires when the machine is in the condition shown in Fig. 6. Fig. 12 shows 85 90 the interlock completed by a return to the condition indicated in Fig. 5.

In Fig. 13 the eyes are shown as completed by coiling the ends of the wires around the bodies thereof, and in Fig. 14 the wires, with 95 their interlocking eyes, are shown detached from the machine.

The stud around which the wires are bent is indicated in the detail drawings by reference-letter c. It has longitudinal motion in 100 tubular standard a, and when at rest is held sheathed in the same by spring c'. (Shown in Fig. 3.) The standard a has partial rotation in a socket formed in base-plate A, and it is

provided with lugs that act as bearings for the pivot b' of handle b . The handle connects at its inner end with the stud-bar and furnishes means for raising the stud and moving the standard. The standard, in addition to the peculiarities hereinbefore noted, has projections a' on its upper end, as clearly seen in Figs. 3, 8, 9, 10, 11, 12, and 13.

The operation of the wire-holding device is as follows: The wires having been laid in the positions shown in Fig. 8, the stud is forced upward and the handle is turned to the right, bringing the projections a' against the wires and cramping said wires between the projections and the stud, as shown in Fig. 9. This position is maintained until the interlock is effected, when the handle is turned to the left to permit the twister-wheels to engage the ends of the wires and complete the eyes, after which the stud is lowered to permit the ready detachment of the eyes from the machine. The bracket B is secured to a standard of the main frame of the machine, and it carries sleeves t and v in vertical alignment with the standard of the stud. Rod or slide s has longitudinal motion in sleeve t , and is provided with head l . The spring t' (shown in Fig. 3) tends to hold the slide in the position shown in Fig. 4, and spline s' , acting in slot t'' of the sleeve, prevents the slide from turning. Slide u is adapted to sleeve v in the same manner that slide s is adapted to sleeve t , and it is provided with head r , that is held when at rest, as shown in Fig. 4, by means of spring v' . Spline u' , acting in slot v'' , prevents slide u from turning. The heads rest near together, as shown in Fig. 4 and other figures, and interposed between them is the anti-friction roller w on the crank end x of the bell-crank lever y . Lever y is fulcrumed on bracket B , and it extends downward and forward to a convenient point, where it is provided with a handle.

Levers d and e have pivotal bearings on base-plate A at points diagonally opposite. They have fingers f and g , respectively, which are slightly forked at their extremities to engage the wires. They also have extensions d' and e' , which connect, through rods h and i , with head l . Levers o and p are pivoted on the lower end of sleeve v . They have extensions q and z , that correspond in function to the fingers of levers d and e . Their motion is at right angles to the direction of the motion of the lower pair of levers, and they are connected by rods m and n with head r . When the wires are cramped, as shown in Fig. 9, the lever y is raised to the position shown in Fig. 5, causing fingers g and f to describe the arcs shown by broken lines in Fig. 4, and thereby carry the ends of the wires over the bodies and into the positions shown in Fig. 10. The lever y is next swung to the position shown in Fig. 6, causing extensions q z to carry the ends of the wires into the positions shown in Fig. 11, while slightly depressing them. A return of the lever y to

the position shown in Fig. 5 will cause the levers f g to carry the ends of the wires to the position shown in Fig. 12, and so complete 70 the interlock. The motions necessary to effect the operation can be made with great rapidity. They permit the operator to maintain an erect position, and they are not particularly tiresome. 75

The means used to complete the eyes by coiling the ends of the wires around the bodies form no part of my present invention. They are, however, set forth generally in Fig. 1. The twister-wheels E are moved up to 80 their work by bell-crank levers I . The hubs of the wheels have slots or projections that engage the ends of the wires, and the wheels get their motion from friction-wheel F when up to their work. The friction-wheel F is 85 driven by a band, H , on wheel G , the two wheels being on the same shaft. The bell-crank levers I are preferably operated by hand-lever O , that has crank-extension N , which connects through rod M with lever L . 90 The lever L is in turn connected with the bell-crank levers through rods K K . Braces S limit the return slide of the twister-wheels. The entire device rests on bed P , which is supported by legs R , or in any suitable manner. 95

The terms "upper" and "lower" and "vertical" and "horizontal" are used throughout the specification and claims in a relative sense on the supposition that the stud around which the wire is bent shall maintain a vertical position and project upward. This position is not, however, absolutely essential. The sleeves t and v , with their slides s and u , respectively, although placed the one above 100 head l and the other below head r , act as lateral guides for said heads and cause them to maintain right lines while moving. They are desirable, but not indispensable, forms of guides. 110

I claim—

1. In a machine for forming interlocking eyes of sections of wire, a stud, a wire-holding device, and bending-levers fulcrumed below the stud and arranged to carry the ends 115 of the wires over the bodies thereof, all in combination, as set forth.

2. In a machine for forming interlocking eyes of sections of wire, a stud, a wire-holding device, and bending-levers fulcrumed to 120 swing in vertical frames and carry the ends of the wires over the bodies thereof, all in combination, as set forth.

3. In a machine for forming interlocking eyes of sections of wire, a rotative tubular 125 standard having projections on its upper end, and a stud having longitudinal reciprocating motion in the standard, in combination, as set forth.

4. In a machine for forming interlocking 130 eyes of sections of wire, a tubular rotative standard having projections on its upper end, a stud having longitudinal reciprocating motion in the standard, and levers fulcrumed

below the stud in a manner to swing vertically past the same, all in combination, as set forth.

5. In combination, a stud, a wire-holding device, a pair of levers fulcrumed below the stud to swing in vertical planes, and a pair of levers fulcrumed above the stud to swing in vertical planes at right angles to the planes of motion of the lower pair of levers, as and for the purpose set forth.

6. In combination with stud *c* and a wire-cramping device, levers *d* and *e*, having fingers *f* and *g*, respectively, as and for the purpose set forth.

15 7. In combination, stud *c*, levers *d* and *e*, having fingers *f* and *g*, respectively, crank-lever *y* *x*, head *l* above the termination of *x*, lateral guides for head *l*, and rods *h* *i*, con-

necting the levers with the head, as and for the purpose set forth.

8. In combination, stud *c*, levers *d* and *e*, having fingers *f* and *g*, respectively, crank-lever *y* *x*, head *l* above the termination of *x*, rods *h* and *i*, connecting head *l* with levers *d* and *e*, levers *o* and *p*, having extensions *q* 25 and *z*, respectively, head *r* below the termination of *x*, rods *m* and *n*, connecting head *r* with levers *p* and *o*, and lateral guides for heads *l* and *r*, as and for the purpose set forth.

In testimony whereof I sign my name in the 30 presence of two subscribing witnesses.

ROBT. FARIES.

Attest:

J. C. HOSTETER,
L. P. GRAHAM.

It is hereby certified that in Letters Patent No. 397,175, granted February 5, 1889, upon the application of Robert Faries, of Decatur, Illinois, for an improvement in "Machines for Forming Interlocking Eyes," an error appears in the printed specification requiring the following correction: In line 121, page 2, the word "frames" should read *planes*; and that the Letters Patent should be read with this correction therein that the same may conform to the record of the case in the Patent Office.

Signed, countersigned, and sealed this 12th day of March, A. D. 1889.
